UNITED STATES PATENT OFFICE

132,986

DESIGN FOR A TOTEM POLE FOR AN ADVERTISING DISPLAY

Edward M. Burnham, San Francisco, Calif.

Application September 30, 1941, Serial No. 103,572

Term of patent 3½ years

To all whom it may concern:

Be it known that I, Edward M. Burnham, a citizen of the United States of America, residing at San Francisco, in the county of San Francisco and State of California, and whose post-office address is 225 Bush Street, San Francisco, have invented a new, original, and ornamental Design for a Totem Pole for an Advertising Display, of which the following is a specification, reference being made to the accompanying drawing, forming a part thereof.

Figure 1 is a front elevational view of a totem pole for an advertising display showing my new design, the back of the article being of the same appearance as the front.

Figure 2 is a side view of the display.

I claim:

The ornamental design for a totem pole for an advertising display, substantially as shown and described.

EDWARD M. BURNHAM.
